UNITED STATES PATENT OFFICE.

CHARLES O. WHITNELL, OF KINGSLEY, IOWA.

SKYLIGHT AND VENTILATING MEANS FOR HOG-HOUSES.

1,216,194.

Specification of Letters Patent.

Patented Feb. 13, 1917.

Application filed May 13, 1916, Serial No. 97,369.

To all whom it may concern:

Be it known that I, CHARLES O. WHITNELL, a citizen of the United States, residing at Kingsley, in the county of Plymouth and 5 State of Iowa, have invented new and useful Improvements in Skylights and Ventilating Means for Hog-Houses, of which the following is a specification.

My present invention pertains to skylights and ventilating means; and it has 10 for one of its objects to provide a skylight designed more particularly for use on hog houses and embodying a section capable of being swung upwardly into an open position, and means through the medium of which said section can be expeditiously and 15 easily raised and adjustably maintained in a raised position.

Another object of the invention is the 20 vision of a skylight embodying a frame constructed with a view to strongly holding glass, and at the same time effectually protecting the glass, and affording channels for the free passage of water.

25 Other objects and advantageous characteristics of the invention will be fully understood from the following description and claims when the same are read in connection with the drawings, accompanying and 30 forming part of this specification, in which:

Figure 1 is an end elevation of my novel skylight with the glass-carrying section as it appears when in closed position.

Fig. 2 is a transverse section taken in a 35 plane in rear of the means for raising and lowering and adjustably fixing the glass-carrying section.

Fig. 3 is a longitudinal, vertical section with the glass-carrying section in raised position.

Fig. 4 is an enlarged detail end elevation 40 illustrative of the longitudinal-central member of the frame for holding the glass.

Similar numerals of reference designate 45 corresponding parts in all of the views of the drawings.

The illustrated embodiment of my invention 50 comprises a base 1 in which is an opening surrounded by an upstanding rectangular flange 2, and hinged at 4 is the frame 3 of the section that is adapted to be swung upwardly and downwardly on the flange 2 of the base. The frame 3 is equipped as illustrated with a 55 longitudinal bar 16, and receiving and movable on the said bar is the eye 18 of an

arm 17. The said arm 17 is carried at one end of a rock shaft which is journaled in a bearing 19 on the base flange 2, and at its opposite end the said shaft merges into an arm 20 which, in turn, terminates in a handle 21. By virtue of this construction, it will be manifest that when the parts are relatively arranged as shown in Fig. 3, the arm 17 will serve to maintain the swinging section in raised position and without liability of the swinging section casually falling. When, however, the handle 21 is pressed toward the right in Fig. 3, the swinging section will be lowered to its closed position on the flange 2 of the base 60 and will be controlled incidental to the downward movement so as to preclude the possibility of breakage. It will also be manifest from the foregoing that when the swinging section is in its closed position and 65 it is desired to open the same for ventilating purposes, it is simply necessary to apply sufficient effort to swing the handle 21 in Fig. 3 toward the left whereupon the swinging section will be raised to and secured in the position shown in the said figure.

The swinging section illustrated comprises the frame 3, glass panels 15, and a guard 16 of woven wire or other reticulated 70 material suitable to the purpose. It will also be observed that the said section comprises a longitudinal member which is shown in detail in Fig. 4 and will be hereinafter specifically referred to. One end 75 of the frame 3 is plain at its upper edge as illustrated and is provided with glass-retaining devices 9 of pliable metal. The other end wall of the frame 3, however, as well as the side walls thereof, are provided with outwardly directed trough-like 80 portions 5; the portion 5 complementary to the end wall being in communication with the portions 5 of the side wall, and the portions 5 of the side walls being open at their 85 ends adjacent to the end wall 8 so as to permit of the free discharge of water therefrom. The outer walls of the trough-like portions 5 are carried upwardly as indicated by 6, and the said wall portions 6 are 90 merged at their upper edges into inwardly and downwardly extending glass-holding portions 7. It will be noticed in this connection that the portions 5, 6 and 7, are set outwardly beyond the major portion of the 95 100 105 110

frame 3 and that therefore the said portions are adapted to support the guard 16 and serve for the fastening of the side edges thereof, the said side edges being bent under the portions 5 as shown in Figs. 1 and 2 with the result that the guard is strongly fastened in position without the assistance of extraneous devices. By reference to Figs. 1, 2 and 3, it will be observed that the outer edges and the inner ends of the glass panels 15 rest within and above the trough-like portions 5, and that therefore the said portions 5 are well adapted to catch water from the panels and convey the same out of the sky-light.

The longitudinal member of the glass-carrying section is fixed in approved manner to the end wall 8 and the opposite end wall of the frame 3. The said member is open at its end adjacent to the wall 8, and is closed at its opposite or inner end. It will also be observed by reference to Figs. 1, 2 and 4, that the longitudinal member is strongly made of a single piece of sheet-metal, and it comprises upper and lower crown thicknesses 10 and 11, side by side up-standing portions 12 and trough-like portions 13, which terminate in inwardly extending lips 14. The bights at the outer edges of the thicknesses 10 and 11 are adapted to rest on the glass panels 15 while the trough-like portions are adapted to rest under and support the panels. From this it follows that the portions 10 and 11 will protect the inner side edges of the panels 15 while the portions 13 will catch any water that may find its way past said edges and will conduct such water out of the sky-light.

40 In the preferred embodiment of my invention, the end wall 8 of frame 3 is provided with a lip, and the retaining devices are carried by the said lip; the said retaining devices being bent against the ends of 45 the panels 15 after the said panels are pushed home in the frame.

I would have it distinctly understood that while I have elected to illustrate the glass holding and guarding portion of my invention on a frame that is adapted to be raised and lowered, the said glass-holding and guarding portion of the invention may be embodied in a skylight frame of any other description without involving depar-

ture from the scope of my invention as defined in my appended claims.

Having described my invention, what I claim and desire to secure by Letters-Patent, is:

1. A skylight comprising a frame having an upright wall on which is a downwardly and outwardly and upwardly extending portion forming an exterior trough, transparent means extending above said trough, and a guard of reticulated material supported on said upwardly extending portion and above the transparent means and having an edge portion that is carried downwardly outside the trough and inwardly under the trough, whereby the guard is secured of itself on the frame.

2. A skylight comprising a sheet-metal frame having side walls and an end wall on the upper edges of which are outwardly and downwardly extending trough-like portions, and also having portions extending upwardly from the outer walls of the trough-like portions and holding portions extending inwardly and downwardly from said upwardly extending portions, transparent means supported on the frame and extending under the holding portions and into the trough-like portions, and a guard of reticulated material supported on said holding portions of the frame and extending downwardly outside the trough-like portions and bent inwardly under said portions.

3. A skylight comprising a frame having an upright wall on which is a downwardly and outwardly and upwardly extending portion forming an exterior trough and also having the upwardly extending portion carried above the trough and equipped with an inwardly and downwardly extending holding portion and forming a bight apertured 95 to support a guard, transparent means extending under the holding portions and above the trough, and a guard of reticulated material supported on said bight of the upwardly extending portion and held by said 100 trough.

In testimony whereof I have hereunto set my hand in presence of two subscribing witnesses.

CHARLES O. WHITNELL.
